ABSTRACT OF THE DISCLOSURE

Apparatus for handling hot metal from a melting furnace comprising three ladles tiltably mounted on a turntable by means of which they may be successively and simultaneously moved between a receiving station where metal is received, a treating station and a pouring station.

This invention relates to hot metal treating facilities for foundries. More particularly it relates to an apparatus for melting, treating and handling large amounts of metal over extended periods of time.

In many plants such as cast iron pipe foundries, it is necessary to operate cupolas for long periods of time at high melting rates and there is a continuous demand for molten metal. Due to many factors, it is impossible to obtain a stream of metal from the cupola which has the desired composition at all times. Therefore, every effort is made to operate the cupola so that the average composition is equal to the desired composition. A forehearth of suitable size to even out the fluctuations in the spout composition is provided and molten metal is taken from the forehearth at the same rate as it is added from the cupola.

Even with the use of a forehearth, it is often either impossible or uneconomical to operate the cupola so as to obtain the desired composition. For example, in melting metal for ductile iron production in an acid cupola the sulfur content is too high and it is necessary to treat the metal to reduce the sulfur. In addition, when high steel charges or low blast temperatures are used and it is desired to obtain relatively high spout temperatures and to maintain high melting rates, the carbon and silicon contents of the melt are generally low. As a result, it is necessary to treat the metal to correct the deficiencies.

Attempts to continuously treat at the cupola spout or in the forehearth have not been completely satisfactory for several reasons. For example, when continuously desulfurizing it is difficult to obtain uniform mixing of or contact between the metal and treating agent, it is necessary to continuously remove slag which will of necessity contain fresh unreacted material, and it is difficult to obtain clean metal from the forehearth. Also, it is often desirable to operate the cupola with raw materials and under conditions which will result in spout compositions which do not average out to a desired composition in the forehearth. In this situation it is not possible to continuously treat or make additions with certainty that the desired composition will result since the forehearth composition is constantly changing in an unknown manner.

Batch treatment in ladles is not satisfactory because the ladles are generally small in size so that it is impractical to obtain an analysis of each ladle. Also, the temperature drop is excessive, and in general the operation cannot economically and satisfactorily provide large quantities of treated metal of the desired composition and temperature.

Accordingly, this invention has for its object the provision of an apparatus which will permit the continuous operation of a melting furnace, the collection of a suitable amount of metal to give a maximum averaging of the metal composition coming from the furnace, the analyza-

2

tion of the collected metal and the treatment of the analyzed metal in an economical operation which provides a substantially continuous supply of metal of desired analysis and temperature.

5 Other objects and advantages of the invention will be readily apparent from the following written description of the invention set forth in the specification and the embodiments illustrated in the drawings in which:

FIGURE 1 is a plan view layout of the new apparatus in which the equipment components are illustrated more or less diagrammatically.

FIGURE 2 is a front elevation view of a ladle car which comprises a 120° segment of the turntable illustrated in FIGURE 1.

15 FIGURE 3 is a plan view of the ladle car shown in FIGURE 2.

FIGURE 4 is a sectional view of a presently preferred embodiment taken along line IV—IV of FIGURE 1.

20 FIGURE 5 is a sectional view of a presently preferred embodiment taken along line V—V of FIGURE 1.

FIGURE 6 illustrates an alternate method of mounting the ladle cover above the ladle at the pouring station so that it may be tilted with the ladle.

25 Turning to FIGURE 1, the apparatus is seen to comprise a turntable 1 mounted adjacent the tapping spouts 2 of a bank of cupolas 3. Mounted on the turntable 1 are three identical large ladles 4, 5 and 6 which are evenly spaced about the turntable. When ladle 4 is adjacent the melting station, ladle 5 is adjacent a treating station and ladle 6 is adjacent a pouring station. Ladle 4 at the melting station receives molten metal from either or both of cupolas 3 through duck's nest basin 7 which is provided to interrupt the flow of metal from the cupolas while the turntable is rotated to move full ladle 4 to the treating station and empty ladle 6 from the pouring station to the melting station.

30 In the open center of the turntable, in fixed position opposite the treating station, ladle tilting mechanism 8 is provided to permit tilting of ladle 5 to assist in slagging operations. Also in the open center of the turntable there is provided a second tilting mechanism 9 for tilting ladle 6 to discharge its contents at the pouring station as needed.

35 Refractory lined covers 10, 11 and 12 are movably mounted above the ladles 4, 5 and 6 respectively to reduce the heat loss due to radiation from the ladles. A gas burner 13 is mounted in the center of each cover, and these may be used as needed to maintain the desired metal temperature. Cover 10 is provided with a cut out 14 through which metal is poured into ladle 4, it is secured to arms 15 which are pivotable at 16 on column 17, and it can be moved away from ladle 4 by means of hydraulic cylinder 18 acting through lever arm 19. In a similar fashion cover 11 is secured to arms 20 which are pivotally mounted at 21 on column 22, and it may be moved away from ladle 5 by means of hydraulic cylinder 23 connected to lever arm 24. Likewise, cover 12 is mounted on arms 25 which are pivotally mounted at 26 on column 27 and is movable by means of hydraulic cylinder 28 acting through lever arm 29.

40 In the embodiment of the invention described herein, the turntable comprises three identical 120° sections 31, 32 and 33 with identical tilting ladles. When these three sections are secured together they form turntable 1 with three evenly spaced ladles 4, 5 and 6 mounted thereon. Each section moves on flanged wheels which ride on tracks 34. The turntable 1 is rotated by means of ring gear 36 attached to its underside, and the driving means consists of a motor 37 acting through gear reducer 38. 45 Each of the ladles 4, 5 and 6 are pivotable on trunnions 39 and a handle 40 is provided on the opposite side of

each ladle whereby it may be rotated about trunnions 39 by means of either tilting mechanism 8 or 9 when the ladle is positioned at either the treating station or the pouring station.

In FIGURES 2 and 3 the turntable section which is used to make up the turntable 1 is shown in detail. It comprises a car mounted on wheels 51 the axles of which are parallel to radii of the turntable circle so that they will follow the curved supporting track 34. Projecting vertically from the car are two posts 52 which are supported by braces 53. Mounted between posts 52 is a cradle 54 comprising a bed 55 having two vertical posts 56 reinforced by braces 57, two side plates 58 and a front plate 59. This cradle is pivotally mounted between posts 52 by means of trunnion axles 60 extending through supports 61 on the car posts 52 and supports 62 on the cradle posts 56. At each of the front corners tongues 63 are connected to the underside of the cradle 54 by means of pins 64 extending through brackets 65. The tongues 63 angle towards the rear center of the cradle and project beyond the rear of the cradle where they are tied together by means of handle 66. A ladle 67 (corresponding to ladles 4, 5 and 6 in FIGURE 1) is seated in cradle 54 with a pair of trunnions 68 which project from opposite sides of the ladle positioned in appropriate cut outs in side plates 58 (see FIGURES 4 and 5). The contents of the ladle 67 may be dumped through ladle spout 69 by applying a vertical force on handle 40 thus causing the cradle 54 with ladle 67 to pivot about axles 60.

In FIGURE 4, ladle 4 on car 31 is in position to receive metal from duck's nest 7. The duck's nest comprises a base support upon which the nest 71 is supported by a collar 72. The nest comprises a base 73 with spaced apart sides 74 between which is supported the metal holding vessel 75. The metal holding vessel or duck comprises a main holding pot 76 and a long spout 77, and it is pivotally mounted in nest 71 by means of pins 78 extending through a pair of ears 79 and adjacent nest sides 74. The spout 77 may be raised to shut off the flow of metal to ladle 4 or lowered to permit metal to flow into ladle 4 through cut out 14 in cover 10. This raising and lowering is accomplished by hydraulic cylinder 80 causing the container 75 to pivot about pins 78. While an empty ladle is being moved into position, the hydraulic cylinder is extended to raise the spout 77 thus cutting off the flow of metal to the ladle and causing the accumulation of metal in holding pot 76.

Ladle 5 is mounted on car 32 and is positioned at the treating station where the metal can be given any desired treatment such as desulphurization. Cover 11 which is mounted on arm 20 is shown in its swing away position where it does not interfere with the introduction of treating and slagging equipment into the ladle. The cover is moved to this position by means of hydraulic cylinder 23 rotating shaft 21 to which arm 20 is secured. Ladle 5 may be tilted by hydraulic cylinder 81 to which is attached a hook 82 adapted to engage handle 66. Cylinder 81 is pivotally mounted between two posts 83 by means of pin 84, and the posts are strengthened by braces 85. A kick out roller 86 rides against cam surface 87 and cam roller 88 on hook 82 to assure that the hook properly engages handle 66.

In FIGURE 5, ladle 6 is shown mounted on car 33 in position at the pouring station. This ladle is dumped by means of hook 90 which engages handle 66 as it is pulled upward by wire rope 91, the hook carries cam rollers 92 which ride against roadway 93 built on a vertical tower 94. Inside the tower a hydraulic cylinder 95 is mounted by means of pin 96 in a vertical direction with the cylinder rod extended from the top of the cylinder. The wire rope 91 is threaded around pulley 97 mounted on the tower and pulley 98 mounted on the end of the cylinder rod 99 and then secured to the tower. When rod 99 is drawn into cylinder 95 hook 90 engages handle 66 and ladle 6 and cradle 54 are pivoted about trunnion pin 60.

In FIGURE 5, ladle cover 12 is not shown since it is essential that it be moved away from the ladle in order that the ladle may be rotated about its pivot point. If it is desirable to keep the cover 12 on the ladle 6 during the pouring operation, the cover may be mounted above the ladle as shown in FIGURE 6. The cover 13 is attached to a cross beam 100 which has arms 101 at its ends. These arms are provided with trunnions 102 which are seated in U-brackets on posts 104 in axial alignment with trunnion pins 60 about which ladle 6 pivots. The back of the cover 13 is supported by a stop, not shown, mounted on tower 94 thus permitting the ladles to move transversely under the cover.

The size of the ladles 4, 5 and 6 will depend upon the melting rate and the amount of time required to analyze and treat the metal at the treating station. For example, if fifteen minutes is required to analyze the metal and to treat the metal with the proper agents to obtain the desired composition while the cupola is melting forty-eight tons per hour, the ladles would be designed to hold twelve or more tons of metal. The ladles should be well insulated to reduce the heat loss and to prevent excessive reduction in metal temperature between the cupola spout and the pouring station. In addition, the provision of the ladle covers greatly reduces the radiation losses from the top of the ladles. The covers are spaced three or four inches from the top of the ladles to permit free relative movement between the ladles and covers in the horizontal direction and to permit the use of the gas burners mounted in the covers. The gas burners together with proper insulation of the ladles permit the metal temperature to be held at the desired level for prolonged periods of time.

This new apparatus is particularly useful in the manufacture of ductile iron pipe. Metal from either a hot or cold blast cupola is received at the melting station. In view of the ability of the apparatus to conserve heat and maintain the desired temperature, the cupola spout temperature can be appreciably lower than is generally the case. As a result even with a cold blast acid lined cupola, high melting rates can be maintained using high steel charges, and the metal temperature obtained at the cupola spout will be adequate.

When a full ladle is obtained at the melting station the turntable is rotated 120° to transfer the ladle to the treating station where samples are taken and the carbon and silicon contents of the metal are quickly determined. Immediately upon the taking of samples, desulfurization of the metal is commenced. This is preferably accomplished by dumping calcium carbide onto the surface of the metal and then violently agitating the bath for a few minutes with compressed air or nitrogen blown through a submerged tube. As soon as the carbon and silicon values are known, the proper amounts of each are injected into the metal. The metal is then transferred to the pouring station by rotating the turntable 120°, where it is poured into transfer ladles for transfer to the casting machine. The metal may be treated with magnesium and ferrosilicon inoculant by placing these in the bottom of the transfer ladle and covering them with a thin layer of scrap metal. However, other methods may be used in which case the metal would be poured into the appropriate treating vessel at the pouring station.

From the foregoing, it is apparent the present invention provides an apparatus which permits batch treatment of metal received from a melting furnace in such a fast efficient manner as to be comparable to continuous treatment methods in results obtained. While there has been illustrated and described the presently preferred embodiment of the invention, this has been set forth as an illustration of the invention and not as a limitation of the invention. It will be apparent to those skilled in the art that changes may be made in the form of the apparatus without departing from the scope and spirit of the invention as set forth in the appended claims.

I claim:

1. Apparatus for handling hot metal comprising metal melting facilities, a turntable positioned adjacent the melting facilities, a receiving station, a treating station and a pouring station evenly spaced around the periphery of the turntable, three open top ladles tiltably mounted on the turntable and evenly spaced thereon so that when any ladle is positioned at any of said stations the other two ladles will be positioned at the other two said stations, drive means for rotating the turntable to successively position each of said ladles at each of said stations, means provided at the receiving station to control the flow of metal from the melting facilities to a ladle positioned at the receiving station, means provided at the pouring station for tilting a ladle positioned therat to discharge its contents, and a ladle cover provided at each of said stations to reduce heat loss from the open tops of the three ladles while positioned at the stations.

2. Apparatus according to claim 1 wherein at least one of the said covers has a gas burner mounted therein so as to direct its flame downward into the ladle positioned thereunder.

3. Apparatus according to claim 1 wherein the melting facilities comprise at least one cupola.

4. Apparatus according to claim 3 wherein the means provided at the receiving station to control the flow of metal comprise a tilttable reservoir positioned to receive cupola metal and having a spout through which metal is delivered to one of said ladles, the reservoir being pivotally mounted at its side opposite said spout, and a hydraulic cylinder provided to pivot the reservoir so as to raise and lower the spout whereby the flow of metal from the reservoir may be controlled.
